US00D757933S

(12) **United States Design Patent**
Lev et al.

(10) **Patent No.:** US D757,933 S
(45) **Date of Patent:** ** May 31, 2016

(54) **DUAL VIAL ADAPTER ASSEMBLAGE**(71) Applicant: **MEDIMOP Medical Projects Ltd.,**
Ra'anana (IL)(72) Inventors: **Nimrod Lev**, Savion (IL); **Mordechai**
Bukhman, Netanya (IL)(73) Assignee: **Medimop Medical Projects Ltd.,**
Ra'anana (IL)(**) Term: **14 Years**(21) Appl. No.: **29/502,037**(22) Filed: **Sep. 11, 2014**(51) LOC (10) Cl. **24-02**

Office Action issued Mar. 17, 2015 in U.S. Appl. No. 14/504,979 by Lev.

(Continued)

Primary Examiner — David Muller(74) *Attorney, Agent, or Firm* — Panitch Schwarze Belisario & Nadel LLP(57) **CLAIM**

The ornamental design for a dual vial adapter assemblage.

DESCRIPTION

FIG. 1 is a front perspective view of a dual vial adapter assemblage in accordance with our new design;

FIG. 2 is a front elevational view thereof;

FIG. 3 is a rear elevational view thereof;

FIG. 4 is a left side elevational view thereof;

FIG. 5 is right side elevational view thereof;

FIG. 6 is a top plan view thereof; and,

FIG. 7 is a bottom plan view thereof.

1 Claim, 6 Drawing Sheets(56)
